UNITED STATES PATENT OFFICE.

ARTHUR B. GROSS, OF ST. PAUL, MINNESOTA, ASSIGNOR TO GROSS METAL PRODUCTS COMPANY, OF MINNEAPOLIS, MINNESOTA, A CORPORATION OF MINNESOTA.

METAL-DOOR CONSTRUCTION.

Application filed June 13, 1927. Serial No. 198,488.

- My present invention relates to the construction of a sheet metal unit or shell including a pair of laterally spaced plates and an internal truss structure therefor, and 5 more particularly to a method of connecting the sheet metal plates forming the shell, whereby they are interlocked against movement in respect to each other in all directions transversely of the shell.
- 10 The invention, while intended for general use, is especially adapted for use in the construction of a hollow sheet metal door.
- To the above end, generally stated, the invention consists of the novel devices and 15 combinations of devices hereinafter described and defined in the claims.
- In the accompanying drawings, which illustrate the invention, like characters indicate like parts throughout the several views.
- 20 Referring to the drawings:
- Fig. 1 is a fragmentary plan view showing the top of a hollow sheet metal door constructed in accordance with the invention and with its upper end closure removed;
- 25 Fig. 2 is a fragmentary detail view in section taken on the line 2—2 of Fig 1;
- Fig. 3 is a fragmentary perspective view of the front plate detached from the door;
- Fig. 4 is a fragmentary perspective view 30 of the back plate detached from the door; and
- Fig. 5 is a fragmentary perspective view of the internal truss structure removed from the door.
- 35 Referring now in detail to the invention, the shell, forming the sheet metal door illustrated, comprises a front plate 6 and a back plate 7, laterally therefrom. These plates 6 and 7, at their longitudinal edge 40 portions, are bent laterally toward each other in substantially the same plane to form the edge portions of the door, only one of which is shown. The edge-forming section of the front plate 6 is relatively wide 45 and indicated by the numeral 8, and the edge-forming section of the back plate 7 is relatively narrow and indicated by the numeral 9. By reference to Fig. 1, it will be noted that the edge-forming sections 8 and 50 9 have abutting engagement at their longitudinal edges and form a relatively tight joint 10 therebetween. The edge section 8 of the front plate 6 is extended at the joint 10 to form a laterally and inwardly offset 55 main angle member 11 which spans the joint 10 and fits in the corner formed by the back plate 7 and its edge section 9.
- Within the door shell is a truss structure 12, for the plates 6 and 7, comprising a corrugated sheet metal plate of a lighter gauge 60 than that of said plates. The corrugations in the plate 12 are of the same depth as the space between the plates 6 and 7, and said corrugations have flat apexes 13 that alternately and directly engage the inner faces 65 of said plates. The corrugated plate 12, at its flat apexes 13, is rigidly and permanently secured by spot welding, as indicated at 14, to the plates 6 and 7. Said corrugated plate 12, at its apex adjacent to the joint 10 is 70 extended to form a laterally and inwardly offset secondary angle member 15 that fits within the main angle member 11. The offset in the corrugated plate 12 at the angle member 15 affords a stop shoulder 16 with 75 which the longitudinal edge of the flange of the angle member 11, which bears against the inner face of the back plate 7, directly engages.
- In assembling the door structure, the 80 truss structure 12 is first welded to the back plate 7. The front plate 6 is then applied in position by an endwise movement to slide its angle member 11 into interlocking engagement with the back plate 7, its edge 85 section 9, the angle member 15 of the truss structure 12, and the stop shoulder 16. The truss structure 12 is then welded to the front plate 6. From the above description it is evident that the interlocking joint between 90 the front plate 6 and the back plate 7 securely and rigidly connects said plates against movement in all directions transversely of the door and holds the edge sections 8 and 9 with their outer faces flush 95 with the one with the other.
- What I claim is:
1. A sheet metal unit comprising a front plate and a back plate laterally spaced the one from the other, said plates having edge 100 portions extending laterally toward each other to substantially edgewise abutting engagement, said front plate having a laterally and inwardly offset main angle member that spans the joint between said plates and fits in the corner of the back plate, and a truss rigidly secured to the back plate and having abutting engagement with the edge of the respective flange of the main angle member, said truss having a laterally and inwardly 105 offset secondary angle member which fits within the main angle member and spans the joint between the front plate and the back plate.
  2. A sheet metal unit comprising a front plate and a back plate laterally spaced the one from the other, said plates having edge 110 portions extending laterally toward each other to substantially edgewise abutting engagement, said front plate having a laterally and inwardly offset main angle member that spans the joint between said plates and fits in the corner of the back plate, and a truss rigidly secured to the back plate and having abutting engagement with the edge of the respective flange of the main angle member, said truss having a laterally and inwardly offset secondary angle member which fits within the main angle member and spans the joint between the front plate and the back plate.

offset secondary angle member that fits within the main angle member.

2. A sheet metal unit comprising a front plate and a back plate laterally spaced the one from the other, said plates having edge portions extending laterally toward each other to substantially edgewise abutting engagement, said front plate having a laterally and inwardly offset main angle member that spans the joint between said plates and fits in the corner of the back plate, and a truss comprising a corrugated sheet positioned between said plates and permanently connected thereto by spot welding at the apex of the corrugations, said truss at one of its apexes having a laterally and inwardly offset secondary angle member that fits within the main angle member, said truss at the secondary angle member having a stop shoulder with which the edge of the adjacent flange of the main angle member abuts.
3. A pair of connected plates, one of which is provided with a lateral extension in the same plane as the adjacent portion of the other plate, said other plate having a laterally offset angle extension fitting in the corner formed by said lateral extension and the respective plate, one flange of said angle extension being parallel to said lateral ex-

tension and in direct contact therewith and its other flange being parallel to the respective plate and in direct contact therewith, and means for holding the angle extension in said corner.

4. A pair of connected plates, one of which is provided with a lateral extension in the same plane as the adjacent portion of the other plate, said other plate having a laterally offset extension fitting in the corner formed by said lateral extension and the respective plate, and a member attached to the plate having said lateral extension and engaging the angle extension to hold the same in said corner.

5. A pair of connected plates, one of which is provided with a lateral extension and an angle member in the corner formed by said plate and its extension, the flanges of the angle member being laterally spaced from said lateral extension and the respective plate to form an angle recess therebetween, said lateral extension and the adjacent portion of the other plate being in the same plane, said other plate having a laterally offset angle extension in said angle recess.

In testimony whereof I affix my signature.

ARTHUR R. GROSS.
